UNITED STATES PATENT OFFICE.

WILLIAM SCHWAGERMANN, OF YONKERS, NEW YORK, ASSIGNOR TO WARD LEONARD ELECTRIC COMPANY, A CORPORATION OF NEW YORK.

CIRCUIT INTERRUPTER.

Application filed March 24, 1920. Serial No. 368,350.

To all whom it may concern:

Be it known that I, WILLIAM SCHWAGERMANN, a citizen of the United States, residing at Yonkers, in the county of Westchester and State of New York, have invented certain new and useful Improvements in Circuit Interrupters, of which the following is a specification.

In general the object of this invention is to provide a circuit interrupter which will be simple in construction and economical to manufacture and have comparatively large capacity for its size in carrying and rupturing heavy currents. A particular feature is the provision of means for rupturing heavy currents without serious arcing or material deterioration of the contacts.

Heretofore it has commonly been the practice in the circuit interrupter art to break the circuit by a wide separation of the movable contacts from the fixed contacts which in itself involves considerable expense in the size of the parts and their assembly. It is also common practice to provide auxiliary means for reducing the arcing such as secondary contacts, magnetic blow-outs, or other special construction for protecting the contacts and minimizing arcing. This still further increases the cost of the interrupter and complication of the apparatus.

By my invention I introduce between the contacts at the time of breaking the circuit a shield of insulating material for interrupting the arc and in the preferred form of my invention I also cause this shield to actually separate the contacts by being thrust between them, and it so overlaps the contacts as to form a barrier to prevent the arc passing around it between contacts. I have found by experiment that very heavy currents can be interrupted in this manner without serious arcing or serious deterioration of the contacts with continued use, and that my improved circuit interrupter may be made simply and of small size.

My invention will be understood from the following description and accompanying drawings illustrating a preferred embodiment of my invention.

Fig. 1 is a front elevation; Fig. 2 is a side view; Fig. 3 is a plan view, and Fig. 4 is a side view of a portion of the breaker with the parts in open circuit position.

The breaker is mounted upon an insulating panel 10 and in this instance has an

over-load coil of the usual iron-clad type, the iron housing being shown at 11 and having side lugs 12 by which it is secured to the panel.

At the top of the housing 11 is shown a support 13 of insulating material shown held in place by an angle piece 14. This insulating support 13 carries the fixed contact 15 of the breaker which is shown as a flat metal strip located in a recess in the face of the support 13 and having its contact surface flush with the face of the insulating support 13. The contact has a screw 16 mechanically and electrically connected therewith and passing back through the support 13 to form a terminal connection 17.

The movable contact 18 of the breaker is shown as a U-shaped sheet metal strip having its face making contact with the face of the fixed contact 15. A flexible conductor 19 is soldered to the contact 18 and makes connection with one line terminal 20 of the breaker. The movable contact 18 is normally pressed against the fixed contact by a sheet metal strip 21 having one portion engaging the trough of the movable contact 18 and the other portion supported by the magnet housing 11. For this purpose the metal strip 21 has one end bent to enter a depression in the housing 11 and also has secured thereto a band 22 which embraces the magnet frame and thus gives a yieldable pivotal connection to the lower end of the strip 21. A screw 23 passes freely through a hole in strip 21 and engages the magnet frame. A spring 24 is located between the head of the screw and strip 21, thus normally forcing the movable contact 18 towards the fixed contact 15. The contact 18 is movable on the inner end of the strip 21 so as to permit the contact to be self-adjusting to the fixed contact 15 for obtaining a good electrical contact therewith.

From the terminal 17 of the fixed contact, a lead extends to the fixed terminal 25 and thence a lead extends to the overload coil of the magnet, the return lead therefrom being shown in dotted lines extending to the line terminal 26.

The iron plunger of the magnet is shown at 27 seated upon an adjustable screw 28 which latter is adjustable in and supported by a bracket 29 extending downwardly from the magnet frame. A rod 30 is connected to the upper end of the plunger

27 and has secured to its upper end a block 31 of the insulating material having an upwardly wedge-shaped extension 32. The upwardly extending part 32 slides against 5 the face of the insulating block 13 and when in its lower position has the upper edge of the extension below the junction of the fixed and movable contacts of the breaker, as well shown in Fig. 2. At the lower 10 end of the plunger 27 is connected a rod 33 having a handle 34, this rod passing centrally and freely through the adjustable screw 28.

The circuit breaker is shown closed in 15 Fig. 2 and the parts in normal running position, the circuit being completed from line terminal 20 to movable contact 18, fixed contact 15, thence through the controlling or overload coil of the magnet to the other 20 line terminal 26. Upon the passage of an abnormal current through the controlling coil, the plunger 27 will be raised and by its connection with the insulating wedge 32 will also cause the latter to be raised 25 and forced between the circuit breaker contacts 15 and 18. This action will quickly and effectively break the circuit and also abruptly rupture any arc by cutting through the path of the current, the parts assuming 30 the position shown in Fig. 4. The wedge or shield 32 is wider than the contacts and forms a barrier to prevent the arc passing around it between contacts and of course the arc cannot pass below it. The parts 35 will remain in this position by reason of the pressure of the movable contact 18 against the face of the wedge 32 and the circuit will remain open until it is again closed when desired by pulling down the 40 handle 34, which will restore the plunger 27 and wedge 32 to their lower positions.

In practice the movement of the wedge 32 over the face of the contacts 15 and 18 in opening and closing the breaker, tends 45 to scour them and thus keep them clean and effective in making good electrical connection. I have found fiber to be a suitable material for the wedge 32 and that it withstands continued use without material deterioration, but obviously any other 50 suitable insulating material may be used.

Although I have illustrated and described 55 one embodiment of my invention, various modifications and other applications may be made thereof without departing therefrom.

I claim:

1. In a circuit breaker, a controlling coil, a fixed contact and a movable contact above said coil, means for yieldably pressing said movable contact against said fixed contact, 60 an insulating element below said contacts and above said coil, a magnetic element controlled by said coil and operatively connected with said insulating element to cause the upward movement of the latter upon 65 the passage of abnormal current through said coil and thereby force said movable contact from engagement with said fixed contact, and adjustable means below said coil for adjusting said magnetic element. 70

2. In a circuit breaker, a controlling coil, a fixed contact and a movable contact above said coil, means for yieldably pressing said movable contact against said fixed contact, a wedge-shaped insulating element below 75 said contacts and above said coil, a magnetic element controlled by said coil and operatively connected with said insulating element to cause the upward movement of the latter between said contacts upon the 80 passage of abnormal current and thereby force said movable contact from engagement with said fixed contact, and a handle below said coil whereby said insulating element may be withdrawn from between said 85 contacts.

3. In a circuit breaker, a controlling coil, a fixed insulating element at one end of said coil, a fixed contact mounted on said element and having its contact surface flush 90 with the face of said insulating element, a movable contact, means for yieldably pressing said movable contact against the contact surface of said fixed contact, a movable insulating element adapted to slide over 95 the face of said fixed insulating element, a magnetic element controlled by said coil and operatively connected with said movable insulating element to cause the movement of the latter upon the passage of 100 abnormal current through said coil and thereby force said movable contact from engagement with said fixed contact, and a handle at the opposite end of said coil from said fixed insulating element whereby 105 said movable insulating element may be moved to permit said movable contact to engage said fixed contact.

WILLIAM SCHWAGERMANN.
